(57) **CLAIM**

We claim the ornamental design for a compressor pump, as shown.

DESCRIPTION

FIG. 1 is an isometric view of a compressor pump showing my new design;

FIG. 2 is a top plan view;

FIG. 3 is a front elevation view;

FIG. 4 is left side elevation view;

FIG. 5 is a rear elevation view;

FIG. 6 is a right side elevation view; and,

FIG. 7 is a bottom plan view.
